(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever. FIG. 1 is a front view of a display screen or portion thereof with graphical user interface showing our new design; FIG. 2 is a front view of a display screen or portion thereof with graphical user interface in accordance with a second embodiment;

FIG. 3 is a front view of a display screen or portion thereof with graphical user interface in accordance with a third embodiment; and,

FIG. 4 is a front view of a display screen or portion thereof with graphical user interface in accordance with a fourth embodiment.

The outermost broken line illustrates the display screen or portion thereof and forms no part of the claimed design. Color may or may not form a part of the claimed design without departing from the design disclosed.
